F. H. YALE

SPRAYING MACHINE

Filed June 14, 1926

Patented Dec. 11, 1928.

UNITED STATES PATENT OFFICE.

FRANK H. YALE, OF ALAMEDA, CALIFORNIA, ASSIGNOR OF ONE-HALF TO CONRAD B. SOVIG, OF SAN FRANCISCO, CALIFORNIA.

SPRAYING MACHINE.

Application filed June 14, 1926. Serial No. 115,857.

This invention relates to improvements in spraying machines and more particularly to machines for spraying hot asphalt, tar and the like. Broadly stated the invention consists of the novel combination and arrangement of the parts of the machine.

The principal object of the invention is to provide a simple, efficient, portable machine for reducing asphalt to the liquid state by 10 heat and pumping the same through flexible conduits or tubes and manually spraying it directly against the surface to be covered. Another object is to provide proper pressure regulation on the liquid, to maintain a uniform flow. A further object is to agitate and 15 maintain a constant uniform temperature and fluidity throughout. Another important object to provide means for reversing the flow of liquid so that the conduits can be emptied and washed clean before shutting down the machine. Other objects and advantages 20 will appear as this description progresses.

In this specification and the annexed drawings the invention is illustrated in the form 25 considered the best, but I do not wish to be understood as confining it to this form, because it may be embodied in other forms and it is also to be understood that in and by the claims following the description it is desired to cover the invention in whatsoever 30 form it may be embodied.

In the accompanying one sheet of drawings, Figure 1 is a side view, showing the vat in vertical section, of a machine constructed in accordance with this invention. Figure 2 is 35 an end view of the same in vertical section on the line II-II.

In detail the construction illustrated in the drawings comprises a portable truck, having 40 the platform 1, mounted at the rear on two wheels 2 on an axle fixed to the platform. The front wheels 3, supporting the front of the platform are mounted upon an axle swinging on a king pin 4, so that the front 45 wheels can cut under the platform to facilitate maneuvering the truck in a limited space, by means of the draft handle 5 pivoted to the front axle thill 6.

The heating tank for containing the liquid 50 asphalt comprises the vat 7, preferably with a rounded bottom as shown in Figure 2, to concentrate the flow of liquid toward the

pump inlet. The vertical side walls of the vat are bent and extend laterally at 8-8 and rest upon the enclosing side walls 9, to which 55 they are fixed, leaving the heating spaces 10-10 on both sides of the vat. These spaces are vented at the top by the holes 11-11 in the extensions 8-8. The opposite ends of the vat are closed by being riveted to the end 60 walls 12-12, that are joined at the corners with the side walls 9-9, to form a complete enclosure for the vat, except at the top. This supporting enclosure for the vat is lagged at 13, with cork tile, or other heat insulating 65 material, covered with sheet metal over its entire exposed outer surface to retain the heat to which the vat is exposed.

One of the end walls 12 is provided with the 70 opening 14, having the transverse bar 15, supporting the end of the gas or oil burner 16, extending beneath the vat and having its opposite end supported in the other wall 12. This burner may be of any desired type, many 75 of which are available on the market, consisting of the self generating type, making its own gas from hydrocarbons as illustrated or of the open burner or blast type or an open fire using wood or other hard fuel may be used. The burner 16 is supplied wth oil fuel 80 through the tube 17, leading to the reservoir 18, located at any point safety remote from the fire box. The fuel is controlled at the burner by the valve 19, and at the reservoir 85 by the shut off cock 20. The top of the platform beneath the vat, forming the fire box floor should be covered with fire brick, sand or other fire resisting material, as at 21.

There are many types of pump available 90 but the preferred form is the double "gear pump" shown, in which two gears fixed upon the shafts 22-23 are revolved within the enclosing casing 24. This casing has the lower inlet 25, and the top outlet 26. The pump is conveniently mounted upon the plate 27, bolted to the end 12 of the vat.

The pump is driven by the shaft 23, extending through the packing gland 28. The drive shaft 23 extends through suitable journal bearings in the gear casing 29, containing 100 a worm gearing, the worm of which is fixed on the end of the shaft 30 of the motor 31, whereby the speed of the motor shaft is reduced to the proper ratio to drive the pump

at about 300 R. P. M. The worm gear is desirable for the present use, because it is self contained and well protected. There are other types of gearing such as sprocket and 5 chain, gears and pinions and the like, that are less expensive, but have certain disadvantages in danger to operatives, exposure to interference and difficulties in lubrication. An electric motor is ideal where such power is available, but it is obvious that internal combustion 10 motors, steam and other forms of prime movers are equally applicable for the purpose.

Since hot tar, asphalt and other heavy liquids are sluggish in flow and may vary in specific gravity within its own mass it is desirable to provide some means for circulating it constantly within the vat, to prevent stratification and lumping. This is accomplished 15 by means of the propeller 32 fixed upon the shaft 23, adjacent to the pump for agitation and circulation of the asphalt.

The motor 31 is wired through a reversing switch 33, so arranged that the motor can 20 be caused to run in either direction, as selected by the hand lever 34 adapted to reverse the contacts accordingly. Where other forms of prime mover are used a reverse gearing must be substituted for the reversing switch 30 33.

The liquid discharged from the pump through the outlet 26, is forced through the outlet pipe 35 that is carried out over the top of the vat and connected with the flexible 35 metallic conduit or tubing 36. The outer end of this tubing terminates in the spray tip 37, provided with a stop valve controlled by the handle 38, for regulating and stopping the flow. To protect the operator from the heat 40 of the tube it is covered with a section of cotton hose or other insulating sheath 39.

To protect the machine from the elements, the vat is covered by the hinged doors, 44-45, hinged to the beam 46, extending across and 45 supported by the end lagging 13-13, and resting upon the extensions 47 fixed to the side lagging 13-13. The motive gearing and connections are protected by a proper housing 48 built therearound and provided 50 with a hinged door (not shown), to permit easy access when desired.

When the valve at 38 is closed the back pressure created in the tube 36, acts on the conventional spring actuated pressure regulator 40, which opens and permits the liquid 55 from the pump to flow back into the vat at 41. This pressure may be regulated by the handle 42 so that obstructions or pressure variations in pump output will not seriously vary the 60 spray discharge at the nozzle 37. To further aid in maintaining a uniform pressure discharge the air chamber 43 is interposed in the discharge line between the pump, the pressure regulator and the spray tip to act as 65 a compressible air cushion compensating for

pressure variations, too sensitive to be handled by the pressure regulator.

This invention operates substantially as follows: The material most in demand for weather proofing, in this class is grade "E" 70 asphalt which must be reduced from a solid to a liquid by heat. This may be done within the vat 7, but where large areas are to be covered as in cement docks, walls of buildings, bridges and the like, it is preferable to melt 75 the asphalt at a central station and deliver by motor tank trucks to the job and keep the vat filled by transferring it there as required; in this manner economy in operation is accomplished and the spraying machine is more 80 portable with a smaller load of material. The tap 49, on the pump inlet may be used to pump liquid from the supply tank into the vat.

When the vat is first filled the burner 16 is 85 lighted and the mass of material therein is maintained at the proper flowing temperature about 140° Fahrenheit, then the switch handle 34 is thrown into the position shown in Figure 1, for pumping out of the vat, 90 through the various mechanisms previously described. The liquid asphalt issuing from the tip 37, in the form of a spray, is directed against the surface to be coated, into which it is driven by the pressure, insuring the 95 maximum penetration and adherence for such a material, which may be evenly and economically distributed according to the skill of the operator. When the operator closes the handle 38, the liquid flows from the pump 100 back into the vat at 41, until the handle 38 is again thrown to the open position. By this invention the asphalt can be directed against ceilings and overhead surfaces without the material dripping and covering the 105 operator and the floor or surface beneath, which is not true where such attempts are made by hand brushing, thus greatly increasing the scope of surface application for asphalting.

When the job is finished and it is desired to put the machine out of commission, the remaining asphalt in the vat 7 is drained out through the tap 50; the switch lever 34 is thrown to the "reverse" position which reverses the motor and causes the pump to reverse and suck back through the tip 37, which is immersed in a bucket of kerosene, distillate or the like, which cuts all the asphalt out of the tube 36, the intervening 115 mechanisms and the pump, leaving every passage clear for the next operation of spraying.

So far as I am aware there is no spraying machine existing that will handle liquids of the consistency of hot asphalt, but it is obvious that cold solutions of tar, paint and the like of similar consistency may be handled according to my invention whether hot or cold, or howsoever reduced to the liquid state.

Having thus described this invention what 130

I claim and desire to secure by Letters Patent is:

5 A spraying machine comprising a vat having surrounding heating spaces; a burner beneath said vat and heating spaces; a pump submerged in said vat and having a shaft protruding within and without the walls of said vat; an agitator mounted upon said pump

shaft within the vat; a motor connected with said pump shaft without said vat; a pressure 10 regulator, an air chamber, a flexible tube and a spray nozzle in the discharge pipe of said pump.

In testimony whereof I have hereunto affixed my signature.

FRANK H. YALE.
